UNITED STATES PATENT OFFICE.

ARTHUR D. LIGHTNER AND EDWARD HOLMES, OF TOLEDO, OHIO, ASSIGNEES TO THE
WILLYS-OVERLAND COMPANY, OF TOLEDO, OHIO, A CORPORATION OF OHIO.

MEANS FOR CRATING ARTICLES FOR SHIPMENT.

Application filed January 30, 1919. Serial No. 274,082.

To all whom it may concern:

Be it known that we, ARTHUR D. LIGHTNER and EDWARD HOLMES, residing at Toledo, in the county of Lucas and State of Ohio, have invented certain new and useful Improvements in Means for Crating Articles for Shipment, of which we declare the following to be a full, clear, and exact description.

10 This invention relates to an improved means for crating articles for shipment, and is more particularly adapted to be used in connection with the shipping of automobile engines.

15 One object of the invention is to provide a system of crating by means of which two or more engines may be arranged in superposed position within a freight car for shipment.

20 Another object of this invention is to provide a system of crating which will accommodate engines of different types and permit of their arrangement together in the car regardless of the relative numbers of each type.

A further object of this invention is to provide a system of crating wherein a plurality of similar crate units are employed, all of which are identical in construction.

30 Further object of this invention relates to economies of manufacture and details of construction as will hereinafter appear from the detailed description to follow.

The objects of the invention are accomplished in one instance by the devices and means described in the following specification, but it is evident that the same may be varied widely without departing from the scope of the invention as pointed out in the appended claims.

A structure constituting one embodiment of the invention, which may be the preferred, is illustrated in the accompanying drawings forming a part thereof in which:

45 Fig. I is a side elevational view of a pair of crate units, each supporting an automobile engine, and separated from each other by a spacing unit.

Fig. II is an end elevational view of the same. 50

Fig. III is a perspective view of a portion of one of the crate units.

Fig. IV is a top plan view of one of the crate units having a type of engine which is supported at four points carried thereby. 55

Fig. V is a top plan view of a crate unit showing the manner of securing a three point supported engine thereon.

Fig. VI is a vertical sectional view taken along the line VI—VI of Fig. I. 60

Fig. VII is a perspective view of the spacing unit.

It is highly desirable in the shipping of an automobile engine to provide a system of crating by which one engine may be superposed above the other in the car, thus increasing the capacity of each car. Moreover, the formation of a system of crating by means of which two or more engines may be superposed upon each other, and the crates 65 securely attached together, provides a ready and convenient manner of handling the engines in loading the same into the freight car and unloading them therefrom. Furthermore in the shipment of automobile engines it has been the practice to enclose each engine in a covered box and place one box 70 above another in the car, but in using this method the boxes soon become broken and can rarely be used more than twice by reason 75 of the fact that the parts are so arranged that in order to properly hold an engine

nails or screws must be employed for securing the parts of each box together, and in removing the engines the boxes are consequently broken so that they are unfit for further use. In the form of crate shown herewith an engine can be firmly secured in each crate without attaching removable covers or strips to the crate and without the use of any securing means which tends to 85 permanently injure the crate or impair its further usefulness as a carrier.

In the drawings, similar reference characters refer to corresponding parts through 95 the several views.

In Figures I and II there are shown two similar crates each containing an engine and separated by a spacing unit to which each crate is securely fastened, the one crate being turned through 180 degrees relative to the other crate.

Each crate comprises a pair of longitudinally extending horizontally positioned base members 10. A vertically positioned side frame member 11 rests upon the upper surface of each of the horizontally positioned members 10, extending in a direction longitudinally thereof, and is firmly secured to the corresponding base member in any desired manner as by means of wood screws (not shown). A pair of transversely extending vertically positioned end members 12 connect the front and rear ends respectively of the vertically positioned longitudinally extending members 11, these parts being firmly secured to each other by means of angle plates 13 connecting to the end portions of the several members and being secured thereto by wood screws or bolts 14 in such a manner as to form an upright box-like structure. The box-like structure thus formed rests upon and is securely supported by the horizontally positioned side members 10.

Vertically extending base members 15 are positioned at the corners of the completed structure, each of said members being adapted to be secured firmly to the under surfaces of the horizontally extending members 10 in any suitable manner, as by wood screws or bolts, and being additionally secured thereto by a plurality of angle brackets 16, each of which is adapted to be secured to the side faces of the base members and the lower surface of one of the horizontally extending members 10. The angle brackets 16 are secured to the corresponding members which they are adapted to connect by means of wood screws or other suitable fastening means 17. One end of the box-like portion of the crate is raised above the upper surface of the remaining portions of the box-like structure by means of a plurality of blocking strips 18 which are adapted to be secured to the upper surfaces of the vertically positioned members 11 and one end member 12 in any desired manner so as to form with said members a rigid box-like structure.

A pair of metal bearing members 19 are secured to the upper surfaces of two of the members 18 at opposite sides of the box-like frame, these plates being firmly secured to the frame by means of wood screws or the like 20 and being provided with threaded opening 21 therein. Corresponding bearing plates 22 are similarly positioned at opposite sides of the other end of the box-like frame. A similar bearing plate 23 is secured to the center portion of the upper face

of one of the transversely extending vertically positioned members 12 in any suitable manner as by wood screws or bolts 24. These end plates are provided with threaded openings 25 similar to those formed in the bearing plates positioned upon the sides of the box-like structure.

A spacing unit 26 adapted to separate and to be secured to two crates comprises a pair of vertically positioned side members 27 and a pair of vertically positioned end members 28. These side and end members are firmly secured to each other for the purpose of forming a box-like structure, open at both top and bottom, by means of a plurality of angular plates 29 adapted to be positioned at the corners of the box-like spacing units and secured to the side and end members by means of wood screws or bolts 30. Openings 31 are formed in the lower edge of the side members 27 of the spacing units and the lower edges of each spacing member are provided with a plurality of bearing portions adapted to rest upon corresponding portions of the uneven upper surface of each crate unit in such a manner that the various side and end portions of the spacing unit will lie in the same plane as the corresponding side and end portions of the corresponding crate unit when the spacing unit is properly positioned upon the upper surface of the crate unit. The upper surface of the crate unit is so formed that when the spacing unit is properly positioned upon a crate unit the upper surfaces of the spacing unit will all lie in a plane parallel to the plane upon which the lower surfaces of the supporting blocks 15 of the crate unit rest.

A plurality of angular brackets 33 are positioned upon opposite sides of each crate unit, being secured to the outer side faces of the blocks 15 by wood screws or other suitable fastening means 34, each of said brackets being provided with a horizontally extending angular portion 35 within which is formed an open ended slot 36. A plurality of brackets 37 are secured to the opposite side spaces of each spacing member, by wood screws or other suitable fastening means 38, in such a manner as to register with the corresponding brackets 33 secured to the side portions of the crate units. An eye-bolt 39 is pivotally secured to each of the brackets 37 in such a manner as to be capable of being positioned within the open ended slot 36 in a corresponding bracket 33 and be firmly locked therein by means of a nut 40 threaded upon the end of the eye-bolt. A plurality of angular brackets 41 are adapted to be secured in a similar manner to the side and end portions of each crate unit for the purpose of securing the same to the next higher spacing unit, the said brackets being adapted to co-operate with corresponding brackets 42 carrying eye-bolts 130

43, similar in all respects to the brackets 37 and eye-bolts 39 above described, and positioned upon the side and end portions 5 of each spacing unit in such a manner as to be adapted to co-operate with the said brackets 41 secured to the crate unit which is positioned below the said spacing unit by means of this construction, the several crate units and the corresponding spacing units 10 inserted there-between may be firmly secured to each other in such a manner as to hold the several parts securely together and form what is in effect a substantially unitary structure.

15 It will be obvious from the preceding description, that when it is desired to ship a quantity of automobile engines these engines can be readily placed in position in crates, the crates being adapted to receive engines 20 of different types, and be firmly secured thereto by means of bolts passing through the ends of the engine supporting brackets and into the bearing plates secured to the upper surfaces of the crates. When a plurality 25 of engines have been secured in position within corresponding crates the several crates may be assembled together in pairs, with a spacing unit interposed between each pair and the upper and lower crate units 30 be firmly secured to the intermediate spacing unit by means of the brackets and eye-bolts previously described in such a manner as to firmly clamp the several parts of the structure together so as to form a firm and 35 rigid structure.

The engines thus crated may be readily removed from place to place by inserting an elevating truck beneath the lower crate unit and raising the same until the supporting blocks 15 are removed from engagement with the floor, when the structure as a whole may be transported to a freight car and properly positioned therein whereupon the truck may be removed in the usual manner. It 45 will be seen that the crates are identical in construction, while the spacing units are also substantially identical, which facilitates the assembly of a pair of crates and a spacing unit to form a single rigid structure. 50 By employing this method of crating engines for shipment not only is it possible to double the capacity of each car, but a considerable amount of time is saved in transporting these engines to the car in that several engines may be carried by a single truck 55 at one time.

It will be apparent that although we have disclosed a shipping unit comprising two crates and a single spacing unit a third 60 crate may be added if desired separated from one of the other crates by a second spacing member.

While we have shown and described in 65 considerable detail a specific embodiment of our invention, it is to be understood that

this showing and description is illustrative only and for the purpose of rendering our invention more clear, and that we do not regard the invention as limited to the details of construction illustrated or described, 70 nor any of them, except in so far as we have included such limitations within the terms of the following claims, in which it is our intention to claim all novelty inherent in our invention broadly as well as specifically.

What we claim as new and desire to secure by Letters Patent is:

1. In a device of the class described, a pair of crates of similar construction each 80 adapted to support an engine, a spacing unit having upper and lower surfaces shaped to conform to the lower and upper faces of the crates whereby the said spacing unit may be interposed between the pair of crates for 85 spacing them apart, and means carried by the crates and spacing unit respectively for securing the same together.

2. In a device of the class described, a pair of similar crates, a spacing unit adapted to 90 be interposed between said crates and means for firmly securing said spacing unit to each of said crates.

3. In a device of the class described, a pair of similar crates, a spacing unit 95 adapted to be interposed between said crates to space the same vertically from each other and means for clamping said spacing unit to said crates.

4. In a device of the class described, a 100 pair of similar engine supporting crates, a spacing unit provided with upper and lower surfaces mating with the lower and upper surfaces respectively of adjacent crates and means for detachably securing 105 the crates and spacing unit together.

5. In a device of the class described, a plurality of engine crates of identical construction, a spacing unit provided with upper and lower surfaces mating with the 110 lower and upper surfaces of adjacent crates respectively, and means for clamping the crates and spacing unit together.

6. In a device of the class described, a pair of crates of similar construction arranged in superposed position, a spacing unit between adjacent surfaces of adjoining crates and means for rigidly securing the crates and spacing unit together. 115

7. In a device of the class described, a 120 plurality of crate units arranged in superposed position, means for securing an engine to each crate, a spacing unit interposed between the adjacent surfaces of adjoining crates, and means for securing the crates 125 and spacing unit together.

8. In a device of the class described, a 130 plurality of crate units arranged in superposed position, a spacing unit interposed between the adjacent surfaces of adjoining

crates, a plurality of registering brackets secured to the side and end portions of the various units, and means carried by corresponding brackets for securing the crates and spacing unit together.

9. In a device of the class described, a plurality of crate units arranged in superposed position, a spacing unit interposed between the adjacent surfaces of adjoining crates, a plurality of registering brackets

secured to the side and end portions of the various units, eye-bolts pivotally connected to one of each pair of registering brackets, and means for attaching the eye-bolts to the other bracket of each pair for securing the crates and spacing unit together. 15

In testimony whereof, we affix our signatures.

ARTHUR D. LIGHTNER.
EDWARD HOLMES.
